Primary Examiner — Sheryl Lane*Assistant Examiner* — Stacey L Hopkins(74) *Attorney, Agent, or Firm* — Matt Catlett(57) **CLAIM**

I claim the ornamental design for a tactical direct charge LED flashlight, as shown and described.

DESCRIPTION

FIG. 1 is a top rear perspective view of the tactical direct charge LED flashlight according to the new design;
FIG. 2 is a bottom rear perspective view of the tactical direct charge LED flashlight illustrated in FIG. 1;
FIG. 3 is a top side perspective view of the tactical direct charge LED flashlight illustrated in FIG. 1;
FIG. 4 is a rear side elevational view of the tactical direct charge LED flashlight illustrated in FIG. 1;
FIG. 5 is a left side elevational view of the search direct charge LED flashlight illustrated in FIG. 1; and,
FIG. 6 is a right side elevational view of the search direct charge LED flashlight illustrated in FIG. 1.
